UNITED STATES PATENT OFFICE

JOHN F. ROBB, OF CLEVELAND HEIGHTS, OHIO

PARTITION MAKER

Application filed March 3, 1927. Serial No. 172,467.

- My invention consists of a novel form of article of manufacture designed to provide a partition strip construction for drawers of desks, tables, buffets and such furniture, whether used in offices or the home. The partition strip of my invention consists of a flexible metal tape of sufficient width to provide the desired height for the partition when in place and the flexibility of the tape permits it to be bent in different directions to enable the various spaces or pockets to be formed by a single length of material or by several cut off strips of the tape bent in the proper directions.
- 15 My partition tape is provided at intervals with nail loops or sockets so that little nails may be driven into place in the bottom of the drawer and engage with such sockets to hold the partition tape in proper position.
- 20 My invention is well illustrated in the accompanying drawings, in which:
- Figure 1 is a perspective view of the flexible metal tape in the condition in which it may be rolled for vendition.
- 25 Figure 2 is a plan view of a piece of the tape outstretched.
- Figure 3 illustrates the manner in which the tape may be bent or arranged in a drawer for use as partition means therefor.
- 30 Figure 4 illustrates the tape with an angular bend.
- Figures 5 and 6 are edge and side views of a modified form of the tape using short pressed out loops for nail socket means instead of long loops or sockets the length of which coincides with the width of the tape.
- 35 My partition tape or material is preferably sheet metal of light standard gage so that it may be rolled to economize space in selling the same in a box. The body of the tape is designated 1 and said body is pressed out to form the nail sockets 2, the manner of rolling the tape being illustrated in Figure 1.
- 40 Since the tape 1 is flexible, it may be bent at different angles and thus one piece may form several sides of a pocket or compartment formed in a drawer or the like. Of course, the tape does not have to be placed in a drawer and could be used on top of a table or other similar place or piece of furniture. Nails 3
- are driven into the supporting base on which the partition tape is mounted. Whereas in Figures 1 to 4, I illustrate nail sockets the entire width of the tape, in Figures 5 and 6, I provide such sockets by narrow pressed out loops 4, either one or both of which may be used in applying the nail securing means to the tape for driving into the base on which it is mounted.
- Having thus described my invention, what I claim as new and desire to secure by Letters Patent of the United States, is:—
1. As a new article of manufacture, a partition tape for making partitions and compartments in drawers or like bases, consisting of a body equipped with nail sockets extending across the width of the body, said body being of a flexible nature permitting the same to be rolled into a composite form.
2. As a new article of manufacture, a partition tape of the class described, made from a flexible metal strip adapted to be wound or formed in a roll provided with attachment means for penetrating devices by which the tape may be held in an upright position on a base.
3. As a new article of manufacture, a flexible metal partition tape having integral pressed out socket members projected from the body thereof to receive attachment means for securing the tape in a position perpendicular to the member to which it is attached.
4. A drawer partition tape of the class described, consisting of a flexible metal body adapted to be rolled up to economize space, and having nail engaging means consisting of pressed out loops integral with the body of the tape, said loops being disposed so as to hold nails parallel to the plane of said tape.
5. An article of the class described consisting of a roll of material adapted to be availed of as a partition construction and including additional means for securing the same to any suitable base member and holding the former in an upright position on said base member so that it constitutes a partition.
- In testimony whereof I affix my signature.
- JOHN F. ROBB.
